CLAIM

The ornamental design for the paving stone, as shown and described.

DESCRIPTION

FIG. 1 is a top plan view of a paving stone showing my new design;

FIG. 2 is a side elevation view thereof, it being understood that all sides are the same; and,

FIG. 3 is a top plan view of a paving stone shown on a reduced scale in position of use with a plurality of like paving stones shown in broken lines for illustrative purposes only and form no part of the claimed design.
